ADJUSTING DEVICE

Alexey J. Stepanoff, Phillipsburg, N. J., assignor to Ingersoll-Rand Company, New York, N. Y., a corporation of New Jersey.

Application October 22, 1942, Serial No. 462,919

5 Claims.

(Cl. 103—89)

This invention relates to pumps, and more particularly to an adjusting device for selectively varying the pitch of the vanes of a rotary pump and for indicating the relative positions of the parts through which movement is transmitted to the vanes for adjusting them.

One object of the invention is to prevent unnecessary wear on the relatively rotary and non-rotary cooperating elements through which force is transmitted to the vanes for changing their angular pitch.

Another object is to enable the relative positions of such cooperating rotary and non-rotary elements to be conveniently indicated at a remote point.

Other objects will be in part obvious and in part pointed out hereinafter.

In the drawing accompanying this specification and in which similar reference numerals refer to similar parts,

Figure 1 is an elevation of a centrifugal pump of a type to which the invention may be advantageously applied and a foundation shown, in section, to support the pump.

Figure 2 is an elevation, partly in section, of an enlarged view of a portion of the pump illustrating the manner in which the invention may be applied thereto.

Figure 3 is a transverse view taken through Figure 2 on the line 3—3.

Figure 4 is an elevation, partly in section, taken through Figure 1 on the line 4—4, and

Figure 5 is a side elevation of a detail taken on the line 5—5 in Figure 4 and looking in the direction indicated by the arrows.

Referring more particularly to the drawing and at first to Figure 1, the pump designated, in general, by 20 is of the vertical axial flow type shown extending into a pit 21 defined by a foundation 22 for pumping liquid 23.

On an intermediate portion of the casing 24 of the pump is an external flange 25 that seats upon the foundation 22 to support the pump, and on the upper end of the pump casing 24 is a motor 26, only a portion thereof being shown, for driving the rotative parts of the pump 20.

The lower end of the pump casing 24 is flared outwardly to define a wide inlet opening 27 for the admission of liquid into the casing 24, and on the portion of the casing 24 lying above the flange 25 is a suitable connection 28 for conveying the discharge fluid from the pump.

Within the casing 24 are upper and lower bearing members 29 and 30 that are arranged coaxially within the casing and with respect to each

other and are connected to the casing by ribs 31. The upper bearing member 29 is bored to accommodate the shaft 32 of the pump. The lower end of the shaft 32 terminates between the bearing members 29 and 30 and carries a box 33 that may be secured fixedly to the shaft in any suitable and well-known manner.

The box 33 comprises a body portion 34 and upper and lower cover plates 35 and 36, respectively, that are secured to the body portion by bolts 37. The upper cover plate 35 has a depending hollow extension 38 that encases the lower end of the shaft 32 and extends to a point below the lower end of the shaft 32 to assist in supporting the vanes 39 of the pump. To this end the lower portion of the extension 38 is provided with apertures 40 that are in axial alignment with apertures 41 in the wall of the body portion 34 to receive trunnions 42 carried by the vanes 39.

Between each vane 39 and its trunnion 42 is a collar 43 that lies in a recess 44 in the outer surface of the body portion 34 to prevent movement of the vanes in the direction of the axis of the pump, and on the portions of the trunnions 42 lying inside of the box 33 are collars 45 that seat against flat surfaces 46 on the box and are secured to the trunnions 42 by pins 47.

Each collar 45 has a crank pin 48 that extends into a slot 49 in a hollow block 50 slideable endwise upon the extension 38. The upper portion of the block 50 is of substantially rectangular shape and the walls 51 of this portion of the block lie in the spaces 52 between the collars 45 and the extension 38 and having oblong slots 53 that extend longitudinally of the block 50 to accommodate the intermediate portions of the trunnions 42. The slots 53, as is customary, are of only slightly greater width than the diameters 40 of the trunnions to permit free endwise movement of the block upon the extension 38 for rocking the vanes 39 about their axes. The side walls of the slots 53 will thus engage the peripheries of the trunnions 42 for holding the block against rotation with respect to the extension 38.

The force serving to actuate the block 50 longitudinally of the pump for rotating the vanes 39 is applied manually through an operating device 54 located in the present instance upon the flange 25 and operatively connected with the block 50 through linkage designated in its entirety by 55. The operating device 54 comprises a casing 56 that may be secured fixedly to the flange 25 in any suitable manner and supports in its upper end a rotary nut 57 having secured

thereto, as by means of a key 58, a hand wheel 59 for rotating the nut.

Threadedly connected to the nut is a rod 60 that extends downwardly along the exterior of the pump casing and has its lower end pivotally connected to a lever 61 that lies across the flared opening of the pump casing 24 and has its other end pivotally connected to a lug 62 on said pump casing. The intermediate portion of the lever 61 is pivotally connected to a rod 63 slideable in the bearing member 30.

The upper end of the rod 63 extends into the lower end of the block 50 and carries a thrust bearing 64 of the anti-friction type which lies in a recess 65 in the lower end of the block 50 and serves to transmit the thrust of the rod 63 to the block 50 for elevating and lowering the said block. The inner race 66 of the anti-friction bearing 64 seats upon a shoulder 67 on the rod 63 and is clamped thereagainst by a nut 68 threaded upon the rod.

The anti-friction bearing 64 is of less length than the recess 65 and the upper and lower end surfaces of said recess constitute seating surfaces 69 and 70, respectively, against which the adjacent ends of the outer race 71 of the anti-friction bearing may abut, accordingly as the rod 63 is moved upwardly or downwardly for rotating the vanes 39 in the desired direction. The recess 65 is, moreover, of sufficiently larger diameter than the outer race 71 to prevent contact between the peripheral surface of the race 71 and the block 50.

As will be readily appreciated the block 50, being interlockingly connected with the shaft 32, must constantly rotate with the shaft during the operation of the pump and inasmuch as the anti-friction bearing is carried by a non-rotary member it is desirable that the said anti-friction bearing be normally maintained out of contact with the seating surfaces 69 and 70 in order to prevent needless wear on these elements. It is for this reason that the recess 65 is so proportioned that the anti-friction bearing may be placed in a neutral position therein so that it will be entirely out of contact with the block 50 after the adjustment of the vanes 39 has been effected.

Inasmuch as the anti-friction bearing 64 is located within the pump so that its position with respect to the seating surfaces 69 and 70 may not be observed by the operator it is, moreover, desirable that means be provided exteriorly of the pump to indicate the position of the anti-friction bearing with respect to the seating surfaces. To this end the rod 60 is provided with a laterally projecting pin 72 that extends into a shoe 73 slideable in a vertical slot 74 in the wall of the casing 56.

In the form of the invention shown the shoe 73 comprises an upper plate 75 and a lower plate 76 that extend transversely of the slot 74 and are suitably spaced with respect to each other to permit of a limited degree of movement of the pin 72 with respect to both plates. The plates 75 and 76 are held thus by clamping plates 77 and 78 that are connected to the plates 75 and 76 by screws 79 and respectively engage the inner and outer surfaces 80 and 81 of the portion of the casing 56 defining the slot 74. The plates 75 and 76 are so proportioned that when the clamping plates 77 and 78 are secured firmly thereto, the latter plates while readily slideable on the surfaces 80 and 81 will exert a binding effect thereon for holding the shoe 73 against unauthorized movement in the slot 74.

On one edge of the outermost clamping plate 78 is a pointer 82, and suitable indicia 83 are inscribed upon the surface 81 for cooperation with the pointer 82 to indicate degree of pitch of the vanes. Preferably, an adjustable seating surface is provided for the pin 72 on the shoe 73 in the form of a screw 84 threaded into the plate 75 to project with its lower end into the path of the pin 72.

The operation of the device is as follows: Whenever it is desired to effect adjustment of the vanes 39, for varying their impelling effect, the rod 60 is raised or lowered by rotating the hand wheel 59. This movement of the rod is transmitted by the lever 61 to the rod 63 to force the outer race 71 against the seating surface 69 or the seating surface 70 for elevating or lowering the block 50, depending upon whether it be intended to increase or decrease the pitch of the vanes 39, and during the axial movement of the rod 60 in either direction the shoe will be moved endwise of the slot 74 by the pin 72. The pin 72 will then engage either the screw 84 or the upper surface of the plate 76 for actuating the shoe 73 upwardly or downwardly.

Thus, if, for example, it be intended to elevate the block 50 the hand wheel 59 is rotated in a direction to cause the rod 60 to move upwardly. The rod 63 will thereby also be caused to move upwardly to bring the outer race 71 against the seating surface 69, and continued movement of the rods 60 and 63 in this direction will cause the block 50 to be moved upwardly and tilt the vanes 39.

During the upward movement of the rod 60 the pin 72 engages the end of the screw 84 and carries the shoe 73 upwardly in the slot 74, and with the screw 84 in a correct position of adjustment the distance between the pointer 82 and the axis of the pin 72 will be directly proportionate to the spaces between the ends of the anti-friction bearing and the seating surfaces 69 and 70 when said bearing occupies a mean position in the recess 65. If then the hand wheel 59 is rotated in a reverse direction to lower the rod 60 slightly until the pin 72 coincides with the pointer 82 the anti-friction bearing will be moved into a position in which the outer race 71 is out of contact with the block 50, and the bearing 64 will, therefore, be protected against such wear as it would otherwise receive if it were permitted to rotate constantly with the pump rotor.

I claim:

1. In an adjusting device, the combination of a pump casing and a shaft therein, vanes connected rotatably to the shaft, means rotatable with the shaft and movable relatively thereto for rotating the vanes to vary their impelling effect, a thrust bearing reciprocable longitudinally of the shaft into engagement with said means to transmit pressure for actuating the said means and being movable out of contact with the said means to selectively prevent the rotation of the thrust bearing with said means, and means located exteriorly of the casing for indicating the position of the thrust bearing with respect to the first-mentioned means.

2. In an adjusting device, the combination of a pump casing and a shaft therein, vanes connected rotatably to the shaft, means rotatable with the shaft and reciprocable with respect thereto to rotate the vanes for varying the capacity of a pump, a reciprocatory support bearing in the casing, a thrust member carried by the support bearing for engagement with said means

to transmit pressure from the support member to said means for rotating the vanes and being movable out of engagement with the said means to selectively prevent the rotation of the thrust bearing with said means, linkage for effecting the reciprocation of the support member, and means associated with the linkage and located at a point remote from the thrust bearing to indicate the position of the thrust bearing with respect to the first-mentioned means.

3. In an adjusting device, the combination of a pump casing and a shaft therein, vanes connected rotatably to the shaft, means rotatable with the shaft and reciprocable with respect thereto to rotate the vanes for varying the capacity of a pump, a pair of abutments carried by said means, a reciprocatory thrust bearing selectively engageable with the abutments and acting to transmit pressure thereto for actuating the said means to rotate the vanes and being movable into and out of contact with the abutments, said thrust bearing being movable into non-contacting position with respect to the abutments, linkage for effecting reciprocatory movement of the thrust bearing, and means associated with the linkage to indicate the position of the thrust bearing with respect to the abutments.

4. In an adjusting device, the combination of a pump casing and a shaft therein, vanes connected rotatably to the shaft, means rotatable with and reciprocable relatively to the shaft for rotating the vanes to vary the capacity of a pump,

5 a pair of opposed abutments carried by the said means, a thrust bearing reciprocable longitudinally of the shaft between the abutments to selectively engage the abutments and acting to transmit pressure thereto for actuating the said means, said thrust bearing being movable into a non-contacting position with respect to the abutments, linkage for actuating the thrust bearing relatively to the abutments, and means associated with the linkage and located at a point remote from the thrust bearing for indicating the position of the thrust bearing with respect to the abutments.

10 15 20 25 30 5. In an adjusting device, the combination of a pump casing and a shaft therein, vanes connected rotatably to the shaft, means rotatable with and reciprocable longitudinally of the shaft for rotating the vanes to vary their impelling effect, a pair of opposed abutments carried by the said means, a thrust bearing selectively movable longitudinally of the shaft into engagement with the abutments and acting to transmit pressure thereto for actuating the said means longitudinally of the shaft, said thrust bearing being movable into a non-contacting position with respect to the abutments, linkage for actuating the thrust bearing relatively to the abutments, and indicating means exteriorly of the casing and operated by the linkage for indicating the position of the thrust bearing with respect to the abutments.

ALEXEY J. STEPANOFF.
